US0D1077044S

(12) United States Design Patent (10) Patent No.: US D1,077,044 S
(45) Date of Patent: * May 27, 2025

(54) TYPE FONT

(71) Applicant: Vanand Holdings Ltd., Limassol (CY)

(72) Inventor: Paola Slongo, Cocquio Trevisago (IT)

(73) Assignee: Vanand Holdings Ltd., Limassol (CY)

() Term: 15 Years

(21) Appl. No.: 29/879,857

(22) Filed: Jul. 13, 2023

(51) LOC (15) Cl. 18-03

(52) U.S. Cl.

USPC D18/24

(58) Field of Classification Search

USPC D18/24, 25; 101/398, 399; 400/484

CPC B41B 1/02; B41B 1/025

See application file for complete search history.
